(57) **CLAIM**

The ornamental design for a face mask, as shown and described.

DESCRIPTION

FIG. 1 is a front perspective view of a face mask showing my new design;

FIG. 2 is a rear perspective view thereof;

FIG. 3 is a front elevational view thereof;

FIG. 4 is a rear elevational view thereof;

FIG. 5 is a top plan view thereof, the bottom view being a mirror image thereof;

FIG. 6 is a right-side elevational view thereof, the left-side elevational view being a mirror image thereof; and,

FIG. 7 is a front perspective view thereof, wherein the face mask is in its folded state.

The broken lines showing of ear loops in FIGS. 1-7 are included for the purpose of showing environmental structure and form no part of the claimed design.
